UNITED STATES PATENT OFFICE.

CHRISTIAN H. SALZMAN, OF CHICAGO, ILLINOIS.

COMPRESSOR FOR HARVESTING-MACHINES.

SPECIFICATION forming part of Letters Patent No. 367,852, dated August 9, 1887.

Application filed June 19, 1886. Serial No. 205,670. (No model.)

To all whom it may concern:

Be it known that I, CHRISTIAN H. SALZMAN, residing at Chicago, in the county of Cook and State of Illinois, and a citizen of the 5 United States, have invented certain new and useful Improvements in Compressors for Harvesting-Machines, of which the following is a full description, reference being had to the accompanying drawings, in which—

10 Figure 1 is a side elevation, partly in section, showing the parts in position to receive the cut grain; Fig. 2, a similar elevation showing the parts in position to compress the cut grain; Fig. 3, a similar elevation showing the 15 parts in position as the cut grain is compressed; Fig. 4, a similar elevation of the compressor-arm, showing its position for the discharge of the bundle.

The object of this invention is to produce a 20 device or apparatus for compressing cut grain into suitable gavels to be bound in automatic or self binders, which will yield during the separation of the grain, and compress a gavel in more than one direction; and its nature consists in the improvements hereinafter 25 described and claimed as new.

In the drawings, A indicates a binding-platform, upon which the automatic or self binder is mounted, as in the Esterly machine, (shown 30 in Patent No. 266,254,) the improvements hereinafter described being substantially based on said machine, and it is mounted upon a frame of gas-pipe or other suitable material.

B indicates the position of the breast-plate 35 upon which the knotter is mounted; C, the needle-arm, which is of the usual form, having the rear extension operating as a separator or divider; D, the compressor-arm; E, the pivoted supporting-block; F, an inward or down- 40 ward projection on the needle-arm; a, pivot of the compressor-arm and the tumbler E; b, slot in the compressor-arm; c, pin or bolt passing through the slot b and connected with the support E; d, arm for operating the sup- 45 porting-block E; d', shaft for operating the arm d; e, link connecting the arm or lever d and the support E; f, adjusting-holes for giving the compressing-arm more or less movement; g, arm or lever for operating the 50 arm D in a forward direction; g', shaft for operating the arm g; h, chain for connecting the arm g with the compressor-arm; i, chain for

operating the arm D in compressing; j, adjusting-holes for the chain i

The binding-platform A in the form shown 55 is adapted for use in a harvesting-machine similar to the Esterly or other machine, where the grain is carried up over the drive-wheel by an elevator and delivered onto a downwardly-inclined binding-platform, and the devices here shown and described are adapted to 60 be operated with any machine which carries a knotting apparatus upon a breast-board located in the position shown by the line B.

The needle, as before stated, is of the usual 65 construction, except that on the side opposite its shaft it is provided with an extension, F, having holes j for receiving the clevis or link which forms a part of the chain i.

The compressing-arm D is best made in the 70 form shown; but this form may be somewhat varied. This arm is pivoted to the supporting block or bar E at a by a stud, pin, or bolt, as may be most convenient. It is provided, also, with a slot or opening, b, so that it may 75 have a limited amount of movement independent of the block or bar E, with which it is connected by the pin c passing from said block through the slot b. The bar E is made in the form shown, and is pivoted to the projection F or upon the needle shaft. It may all be in one piece, or the pivotal extension may be made separately and be bolted on, and it has a vertical movement to the extent of the movement of the arm d. This supporting block 85 or bar E is connected by the link e with the operating arm or lever d, by which it is held and operated.

The compressing-arm is connected with the projection F of the needle or needle-shaft by 90 the chain i, which chain may be adjusted by means of the holes j in the projection F. The compressing-arm is also connected with the partly-rotating arm or lever g by means of the chain h, which holds it when in the position 95 shown in Figs. 1 and 2.

In operation, the needle and the compressor-arm are in the position shown in Fig. 1, when the grain for the gavel or bundle is to be received, and grain may be forced down or in, 100 by ordinary packers or other devices, against the arm D until the desired amount is collected. The needle then commences to rise; but before it rises the compressing-arm D falls backward

to the position shown in Fig. 2, which relieves the pressure which the needle would otherwise have, and affords it an easy passage through the grain flowing to or resting upon 5 the binding-table A, and thus affords an easy separation between the grain to be bound and the advancing grain. When in this position it will be seen that both of the chains *h* and *i* are nearly or quite taut, and from the position 10c shown in Fig. 2 the further movement of the needle or its shaft brings the strain upon the chain *i* and causes the compression-arm to return with a movement equal to that of the advance movement of the needle-arm C, so that 15 15 when the needle is in position for the operation of the knotted or twister the parts will be substantially in the position shown in Fig. 3, where they are firmly held until the operation of the knotted is completed, thus giving the 20c bundle a positive compression from both front and rear, and which, owing to the curved form of the acting parts, almost encircles the bundle, giving it when formed a better shape than is given to it when the compression is 25 from one side only, and this arrangement, also, as before stated, gives the needle a free and easy movement through the grain and an easy division of the gavel from the flowing stream of grain. 30 The shafts *g* *d*' are extended out and operated by cams at their outer ends, which gives the arms or levers *g* *d* their required movements at the proper times. When the needle-arm starts back, the arm *d* throws the compressor into the position shown in Fig. 4, in which position the bundle is easily discharged from the machine. As the point of the needle passes below the breast-plate B the arms *g* and *d* throw the compressing-arm into the position 35 40 shown in Fig. 1, ready for the reception of a succeeding gavel, at which point it remains until the gavel is collected, when the described operation is repeated.

What I claim as new, and desire to secure by Letters Patent, is—

1. The combination, with the needle-arm C and pivoted compressing-arm D, of the chain *i*, attached to the compressing-arm, and the projection F, located on the needle-arm and provided with a series of holes, *j*, for receiving a clevis or link on the chain *i*, substantially as described. 45

2. The combination, with the needle-arm C, chain *i*, and pivoted compressing-arm D, having slot *b*, of the pivoted block E, having pin *c*, engaging said slot, the link *e* and the lever *d*, having adjusting-holes *f* for attachment of said link, substantially as described. 55

3. The combination, with the needle-arm C and the pivoted compressing-arm D, of the arm *g*, chain *h*, connecting said arm *g* with the compressor, the projection F on the needle-arm, and the chain *i*, connecting the compressor with said projection, the latter being provided with adjusting-holes *j* for attachment of said chain, substantially as described. 65

4. The combination, with the needle-arm C, having projection F, and the compressing-arm D, having slot *b*, of the chain *i*, connecting the projection F and arm D, the tumbler-block E, 70 having a pin, *c*, engaging the slot *b*, the lever *d*, and the link *e*, substantially as described.

5. The combination and arrangement of the arm *g*, chain *h*, pivoted compressor-arm D, block E, link *e*, and lever *d*, with the projection F and chain *i*, substantially as set forth. 75

6. The combination, with the needle-arm C, having projection F, and the pivoted compressing-arm D, of the tumbler-block E, adjustable link *e*, lever *d*, arm *g*, and chains *h* *i*, 80 substantially as described.

CHRISTIAN H. SALZMAN.
